JOINTED FOLDABLE SKELETAL SUPPORT

Jacob Bierman, Los Angeles, Calif., assignor to B. & G. Magic Chair Company, Los Angeles, Calif., a copartnership

Application October 13, 1953, Serial No. 385,758

6 Claims. (Cl. 155—148)

This invention relates to a jointed foldable skeletal support more particularly intended as a means for supporting chairs, stools, and tables, but applicable also to various other uses.

The present application has considerable in common with my copending application for patent on a jointed foldable skeletal frame, filed March 19, 1953, Ser. No. 343,476. It is an object of the present application to improve upon the jointed structure disclosed in said copending application, as well as to improve upon the foldable feature of the device, as will hereinafter appear.

Accordingly it is among the objects of the present invention to provide for using pipe sections in a more satisfactory and economical manner in the construction of a foldable support for seats, tables and other foldable structures.

Another object of the invention is to provide a jointed skeletal support which is folded up and unfolded according to a different principle of operation which expedites putting the device into a usable condition and folding it up after being used.

Still another object is to provide, in conjunction with the improved foldable portion of the device, improved means for securely maintaining the extended foldable structure in its operative position so that it will support an overlying structure in a more stable and satisfactory manner.

Also a more specific object is to provide a structure wherein the fold up and extension operations may be performed in a more satisfactory manner, and wherein the extended supporting structure will stand up in a stable dependable manner and be well adapted to support as heavy a weight as will ever be deposited upon the article of furniture of which it forms a part.

Also it is a specific object of the present invention to provide an improved, streamline joint structure between relatively turnable pipe sections.

Other objects, advantages and features of the invention will hereinafter appear.

Referring to the accompanying drawing, illustrative of a preferred, reduced to practice embodiment of the invention,

Fig. 1 is an elevational view of the chair in its operative position, dotted lines indicating the chair backrest shown in its infolded position.

Fig. 2 is a bottom plan view of the structure shown in Fig. 1 with the backrest shown in its infolded position.

Fig. 3 is a bottom plan view of the device as shown in Fig. 2 except that the parts of the supporting leg structure are shown at an intermediate step toward the folded position.

Fig. 4 is a view similar to Figs. 2 and 3 showing the supporting leg structure in the completely infolded position. In this view there is a dotted line indication illustrating an intermediate operational step.

Fig. 5 is a side elevation of the device showing the same in its completely infolded position. This view may be considered as looking at the side of the device located at the lower side of Fig. 4.

Fig. 6 is a transverse fragmentary sectional detail on line 6—6 of Fig. 4, the scale being enlarged.

Fig. 7 is an enlarged fragmentary side elevation of one of the jointed portions of the device.

Fig. 8 is a longitudinal section on line 8—8 of Fig. 7.

Fig. 9 is a transverse section on line 9—9 of Fig. 7.

Referring in detail to the drawing, the foldable skeletal support provided by this invention comprises, when

2

viewed in its operative position shown in Figs. 1 and 2, a rectangularly U-shaped member 10 which is of a one piece, rigid character and by preference, as shown, is made of a metallic tubing. This U-shaped member has a basal run 11 to rest on a horizontal supporting surface and at such time the upper end of each limb 12 of said U-shaped member is located in a downwardly spaced relation to a chair bottom 14 or other horizontally disposed member, for example, a table top which is supported by the foldable skeletal structure provided by this invention.

When the basal run 11 of the aforesaid member 10 is resting upon a supporting surface it cooperates with a pair of angular members 17 each of which is of an inverted L shape, the downwardly directed limb 18 of each of these two members forming a leg which, as shown in the drawing, underlies a corner portion of that side of the seat member 14 which is opposite to the aforesaid U-shaped member 10. Each of said members 17 has a horizontal top run 20, the run 20 of one of said angular members extending in a generally parallel direction in relation to that of the other. In relation to each inverted L structure considered as a whole, each run 20 terminates in a short return run 21, well shown in Fig. 1. At its lower end each of said return runs is swiveled to the upper end portion of the U limb 12 at its side of the structure, one at 21a and the other at 21b.

The preferred means for swiveling each of said return runs to the underlying U limbs is shown in detail in Figs. 7, 8 and 9. In Fig. 8 one of the aforesaid short return runs 21, which like the remainder of the foldable structure, is of a tubular character, has fitted into it one end portion of a plug 25, said plug being provided with a threaded socket 26 into which is screwed a lock screw 27 that is inserted through a suitable aperture provided for it in one side of the tubular part 21. That part of the plug 25 which projects from the tube 21 is turnably fitted within the upper part of the tubular U limb 12, but it is limited to a 90 degree turn within said limb by means of a stop screw 27 carried by the U limb, the inner end portion of said stop screw 27 cooperating with an arcuate groove 28 formed in the adjacent portion of the plug 25. The arcuate groove 28 cooperates with the screw 27, not only to limit the turning movement of the part 12 in relation to part 21, but it prevents these two parts from being separated from each other.

At one side of the seat member 14 the horizontal run 20 of the member 17 at that side of the structure is turnably secured to said seat member by means of two, spaced apart clips 29 and 30 which are secured to said seat member and which have arcuate mid-length portions which loosely fit over said run 20. The midlength part of the clip 30 is longitudinally slotted at 31 and a radially extending pin 32 projects into said slot from said run 20 to prevent said run from shifting in an endwise manner. At the opposite side of the seat member twin, one-piece clips 33, each have arcuated, spaced apart resilient lips 34 to spring over opposite sides of the run 20 at that side of the structure, detachably to hold said run in its operative position. One of said clips 33 carries at its mid-length a vertical pin 33a, basally welded to the clip at 33b, this pin normally fitting within two alined holes in the run 20 to prevent endwise shifting of the latter.

In order to illustrate a desirable use of the invention the part 14 is shown as a chair bottom equipped with a swingable backrest member 35. Said backrest member is shown comprising a plate portion 36 having attached to it two twin J-shaped rods 37, the hooked end portions of which are pivoted at 38 to suitable strap iron clips 39 shown secured to the under side of the chair bottom 14 by means of screws 40. When said backrest member 35 is in its inswing position shown in dotted lines in Fig. 1 and in full lines in Fig. 5, and the skeletal foldable structure comprising the aforesaid members 17 and 10 are also in the folded position, the whole structure assumes the compact arrangement shown in Fig. 5.

Operation

Preferably the first step in the folding up operation is to swing the backrest 35 from the full line to the dotted line portion of Fig. 5.

Assuming the leg forming structure of the device to be

in the extended seat supporting position shown in Figs. 1 and 2, the first step in folding up said leg structure is to pull slightly away from the seat member 14 the horizontal run 17 which is releasably gripped between the arms of the clips 33 (see lower portion of Fig. 4). In doing this said horizontal run will also be withdrawn from the pin 33a (see Fig. 6). After this horizontal run has been pulled clear of said clips 33 it will, together with the leg 18, which it carries and the U-shaped member 10, be swung in a clockwise direction through an angle of 90 degrees around the swivel joint 21b until it assumes the position shown in Fig. 3, where the partly folded run 29 and leg 18 carried thereby are shown located at an intermediate point of the folding up operation. Next, said parts 18 and 20 will be swung farther in a clockwise direction through an angle of a little more than 90 degrees until the part 20 extends alongside its mate 20 and together therewith is in an underlying relation to the adjacent side portion of the seat 14. Then the final step of the folding up of the leg structure will be performed, said step consisting in swinging both the side by side positioned L-shaped members and U-shaped member against the bottom face of the seat member to the position shown in Fig. 4.

I claim:

1. A foldable skeletal support comprising, when viewed in its operative position a rectangularly U-shaped member having a basal run to rest on a supporting surface, and a pair of leg members each of an inverted L shape and each having a horizontal limb which normally is parallel to that of the other, said horizontal limbs being positioned to underlie and support a seat member and each terminating in a downwardly directed short return run, one of said return runs being swiveled to one of the upper ends of the aforesaid U-shaped member and the other of said return runs being swiveled to the other of the upwardly directed ends of said U-shaped member.

2. The subject matter of claim 1 and means to permanently, turnably attach the horizontal run of one of said leg members to the under side of said seat member, and means including a swivel joint to detachably attach the horizontal run of the other of said leg members to the under side of said seat member, so that when the latter run is detached said skeletal support may be swingably folded up and disposed in a closely underlying relation to the under side of the seat member.

3. A foldable skeletal support comprising, when viewed in its operative position a rectangularly U-shaped member having a basal run to rest on a supporting surface, and a pair of leg members each of an inverted L shape and each having a horizontal limb which normally is parallel to that of the other, said horizontal limbs being positioned to underlie and support a seat member and each terminating in a downwardly directed short return run, a joint means swiveling one of said return runs to one of the upper ends of the aforesaid U-shaped member, a joint means swiveling the other of said return runs to the other of the upwardly directed ends of said U-shaped

member, means to permanently turnably attach the horizontal run of one of said leg members to the under side of said seat member, means to detachably attach the horizontal run of the other of said leg members to the under side of the same seat member, so that when the latter run is detached said skeletal support may be folded up and positioned in a closely underlying relation to the under side of said seat member, and means carried by the aforesaid swivel joint means of the detachable leg member to limit the turning movement of its short return run in relation to that arm of the U-shaped member to which it is swiveled.

4. The subject matter of claim 3 and said joint means carried by the detachable leg member comprising a plug and a tubular part into which an end portion of said plug turnably fits, and a stop member projecting radially from said end portion of said plug and having a working fit in said slot to travel therein through an arc of substantially ninety degrees.

5. A foldable skeletal support comprising, when viewed in its operative position a rectangularly U-shaped member having a basal run to rest on a supporting surface, a pair of leg members each of an inverted L shape and each having a horizontal limb which normally is parallel to that of the other, said horizontal limbs being positioned to underlie and support a seat member and each terminating in a downwardly directed short return run, one of said return runs being swiveled to one of the upper ends of the aforesaid U-shaped member and the other of said return runs being swiveled to the other of the upwardly directed ends of said U-shaped member, means to permanently turnably attach the horizontal run of one of said leg members to the under side of said seat member, and means comprising clips with resilient lips

35 between which the horizontal run of the other of said leg members is normally releasably attached to the under side of said seat member, so that when the latter run is withdrawn from between said lips it may, together with said U-shaped member be swung through an arcuate path 40 extending at a right angle to the seat bottom till the parts of the leg skeletal support are in an overlying relation to each other and then are swingable to an underlying relation to the seat member.

6. The subject matter of claim 5 and at least one of 45 said clips having a pin extending removably through said horizontal run engaged by said clips.
